DESIGN FOR A TOOL CHEST OR THE LIKE

Joseph B. Federico, New Baltimore, Mich., assignor to Master Metal Products, Inc., Buffalo, N. Y., a corporation of New York

Application October 1, 1947, Serial No. 141,707

Term of patent 14 years

(Cl. D58—12)

To all whom it may concern:

Be it known that I, Joseph B. Federico, a citizen of the United States, residing at New Baltimore, in the county of Macomb and State of Michigan, have invented a new, original, and ornamental Design for a Tool Chest or the like, of which the following is a specification, reference being had to the accompanying drawing, forming a part thereof.

Figure 1 is a perspective view of a tool chest or the like, embodying my new design. Figure 2 is a rear view thereof on a reduced scale. Figure 3 is a bottom plan view of the same.

I claim:

The ornamental design for a tool chest or the like, substantially as shown.

JOSEPH B. FEDERICO.
